His Attorney

UNITED STATES PATENT OFFICE.

EDWARD R. CONNERS, OF CINCINNATI, OHIO, ASSIGNOR TO THE PRECISION TRUING MACHINE AND TOOL COMPANY, OF CINCINNATI, OHIO, A CORPORATION OF OHIO.

ABRADING PENCIL.

Application filed September 6, 1921, Serial No. 498,732. Renewed October 16, 1925.

To all whom it may concern:

Be it known that I, EDWARD R. CONNERS, a citizen of the United States, residing at Cincinnati, in the county of Hamilton and 5 State of Ohio, have invented certain new and useful Improvements in Abrading Pencils, of which the following is a specification.

My invention relates to abrading pencils 10 similar in character to those shown and described in my co-pending applications for Letters Patent on devices for truing and dressing grinding wheels, Serial No. 366,970, filed March 18, 1920, issued as Patent No. 15 1,395,392, dated November 1, 1921, and on mechanism for truing and dressing grinding wheel, Serial No. 415,403, filed October 7, 1920, issued as Patent No. 1,395,394, dated November 1, 1921, and is an improvement 20 upon the abrading pencils therein disclosed.

A usual means heretofore employed in truing and dressing grinding surfaces of grinding wheels has been a diamond tool, comprising a diamond, made to contact the 25 grinding surface of the grinding wheel, but diamonds have become very scarce and very expensive, and it is one of the objects of my invention to dispense with the use of the same.

30 It is the object of my invention further to provide a rotatable abrading stub or pencil, hereinafter called a pencil, so positioned that its axis of rotation is presented toward the grinding wheel with which it is to coat 35 for the purpose of truing or dressing, and with novel means for insuring correct positioning of the same; further, to provide a rotatable abrading pencil arranged to make end-contact, preferably with a substantially 40 frusto-conical end abrading face, with the grinding surface of the grinding wheel, or, to provide a rotatable abrading pencil for the purpose mentioned which has an end-contact face surrounding a center space 45 which is coincident with the axis of rotation of the rotatable abrading pencil, and to provide such devices with a securing part which is definitely concentric to the axis of rotation of said rotatable abrading pencil, concentric to the apex of the frusto-conical 50 abrading face when employed, and concentric to said center space.

It is the object of my invention further to provide a rotary abrading pencil preferably 55 of materially less diameter than the diam-

eter of the grinding wheel with which it coacts, and having an axis of rotation presented toward the grinding wheel to be trued, and acting with a swirling abrading motion on the rotating grinding wheel, for 60 truing and dressing the same, and to provide said rotary abrading pencil with a securing periphery truly concentric with its axis of rotation.

As heretofore explained in my aforementioned copending applications, I prefer to provide a rotary truing or dressing abrading pencil which is of a texture much harder than the texture of the grinding wheel to be trued or dressed. I have found it possible to produce abrading pencils of exceptional hardness and durability. I have found, however, that due to the extreme heat and pressure employed in forming such pencil, it is difficult to control concentricity of 75 its periphery with the axis of its bore, and difficult to produce such pencil with a periphery at its end arranged to be grasped so firmly in holding devices as to securely hold the abrading pencil and cause proper 80 rotation of the abrading end of the pencil. I have overcome these objections and difficulties by my improved device.

The invention will be further readily understood from the following description 85 and claims, and from the drawings, in which latter:

Fig. 1 represents a side elevation of an abrading pencil in its crude form.

Fig. 2 is a side elevation of an abrading 90 pencil showing one end thereof provided with a rabbet for the reception of a truing ring and its other end provided with a frusto-conical end abrading face.

Fig. 3 is an end elevation of the same 95 viewed from the attaching end.

Fig. 4 is an axial section of the same shown in an exemplified mold.

Fig. 5 is an axial section of my improved device in completed form.

Fig. 6 is a perspective view of my improved device, in connection with an exemplifying truing device, shown in axial section on the line 6-6 of Fig. 7, and in coactive relation in an exemplifying grinding machine, partly broken away; and 105

Fig. 7 is a cross-section of the same, taken on the line 7-7 of Fig. 6.

The abrading pencil in an exemplifying form is shown at 11. It is of extremely hard 110

substance, preferably much harder than the hardness of the grinding wheel, shown at 12, of the grinding machine. The abrading pencil acts on the grinding face 15 of the grinding wheel. The tail-stock of the grinding machine is indicated at 16, the tail-center at 17, and the rotating work at 18, rotated in suitable manner, or as shown and described in my aforesaid copending applications.

10 The abrading pencil may for instance be a carborundum product produced under extreme heat, for instance under the heat of an electric arc, and of granular structure, and be formed under great hydraulic pressure, 15 the grains 21 being fixedly bound together in the structure and forming a surface having interstices 22, which may also be termed recesses or pores, therein. (See Fig. 5). The texture of the abrading pencil is preferably 20 coarser than the texture of said grinding wheel.

I have in Fig. 1, at 25, shown the abrading pencil in its crude form as it is received from the hydraulic press and furnace 25 in one of the forms in which I prefer to produce the same; although if desired, the same may be produced with one of its ends reduced in diameter, as shown at 26 in Fig. 2.

30 The pencil, owing to the intense heat to which it has been subjected, the hardness of its ingredients, and the hardness to which it has been reduced while being formed, is liable to be warped, to be uncertain in its cross-sectional dimensions and form, and in the 35 axial alinement of its parts. The cross-sectional irregularities or the irregularities in axial parallelism are unimportant as far as the abrading action upon the grinding wheel is concerned, provided that the abrading 40 pencil is securely held so as to prevent shifting or wobbling while in operation and so that its physical axis shall be substantially coincident with its axis of rotation.

45 For providing these latter conditions, I provide one end of the abrading pencil with a ring 28, whose outer periphery is concentric with the mesne physical axis of the abrading pencil, so that, when the ring is fixed in a rotatable holder, exemplified as a 50 chuck 29, the abrading pencil will rotate with its physical axis substantially coincident with its axis of rotation.

The abrading pencil further, while being formed, is preferably provided with an axial bore 30. Thus formed, the abrading pencil is a cylindrical abrading body provided with a central or axial space. The axis of a pencil of this character, which is coincident with its axis of rotation, is a neutral point, 55 that is to say, a non-rotating point. In the absence of the axial bore, the pencil would form a point at its axis unduly protruding in axial direction, due to lack of wear thereon, and would form a point liable to gouge 60 into or form detrimental marks or scores in

the grinding wheel. To avoid such detriment and to provide a pencil which will produce an even surface upon the grinding wheel, I provide the central space or axial bore referred to.

I prefer to provide one end of the body of the abrading pencil with a rabbet 32, in which the ring 28 is received. I prefer that the outer periphery of the ring shall be cylindrical and substantially coincident with the cylindrical projection of the outer periphery of the body of the pencil. I prefer to provide the abrading end of the abrading pencil with a frusto-conical abrading face 33.

The rotary abrading pencil is presented endwise toward the rotating grinding face, at one side of the axis of rotation of the abrading pencil, being preferably presented toward the grinding face so that its axis of rotation is at an angle at one side of a right angle to the axis of rotation of the grinding wheel, as exemplified in Fig. 6, or at an angle to the vertical plane in which said right angle is located, or so that said axis of rotation is located in said vertical plane at an angle to a radial line of the grinding wheel, whereby its axis of rotation is a chord to the circle of the grinding wheel, or in a direction including both said angles.

Suitable rotation is imparted to the grinding wheel and to the work, the directions of rotation of the same being indicated respectively by the arrows *a* and *b*. In the present exemplification, the abrading pencil is normally at rest and rotation is imparted thereto, in the direction of the arrow *c*, by contact at one side of its axis of rotation with the grinding wheel.

Movement lengthwise of the axis of rotation of the grinding wheel is caused between the grinding wheel and the abrading pencil, as well as between the grinding wheel and the work, preferably for causing alternate contacts between the work and the abrading pencil on the one part and the grinding wheel on the other part, all as more fully explained in my aforesaid copending applications.

In the present exemplification, the ring end of the abrading pencil is received in the chuck 29, the jaws 35 of which are snugly received about the outer periphery of the ring, the jaws being pressed toward each other by means of a screw 36, for clamping the abrading pencil between said jaws, and firmly holding the abrading pencil by contact of the jaws with the ring so as to prevent shifting or wobbling of the abrading pencil and to hold the abrading pencil so that its mesne axis is coincident with its axis of rotation. Other characters of chucks and holding devices may also be employed to hold or support the abrading pencil.

The chuck 29 is secured to a shaft 38, as by a pin 39, the shaft rotating suitably in a barrel 40, rotation of the shaft and of the abrading pencil being maintained between the abrading pencil and the wall of the mold being provided with a filling 56, as of molders' clay. The arrangement forms an annular space 57 between the reduced end 26 of the body of the abrading pencil and the wall 58 of the mold. 70

5 tween intervals of contact of the abrading pencil with the grinding wheel, by means of a fly-wheel 41, fixed to said shaft, and rotating in an enlargement 42, forming a cup received over the fly-wheel, a cover-plate 10 43 closing said cup. A bushing 45, is located in the barrel and is fixed therein by a set-screw 46. Ball-bearings 47, 48, are located at the respective ends of the bushing, these ball-bearings being combined 15 radial and end-thrust bearings.

The barrel is secured relatively to the grinding wheel, as by providing a clamp-bearing 51 received about the barrel. The barrel may be adjusted axially in said 20 clamp-bearing. A clamp 52 is secured about the tail-center 17, the clamp and clamp-bearing being connected by an arm 53, so arranged as to present the end of the abrading pencil at proper angle to the grinding 25 surface of the grinding wheel.

The movement between the contact or impinging portion of the rotary abrading pencil and the grinding surface is preferably a swirling movement at the line of contact, 30 due, for instance, to the variations of distance along said line of contact from the axis of rotation of the abrading pencil, resulting in a wiping effect of the abrading pencil on the grinding surface, for wiping or drawing out the grinding offal from the interstices or pores of the grinding surface, and acting, throughout a portion of its contact-line, on the grains of the granular grinding surface with a motion different 40 from the direction of grinding motion of the grinding surface upon the work, for sharpening the grains of the granular grinding surface.

The rotary abrading pencil is of comparatively small diameter with relation to the diameter of the grinding wheel and is arranged to make substantial end-contact with said grinding wheel in such manner that this end-contact shall preferably be at 50 one side only of said axis of rotation, whereby the end-contact surface of the rotary abrading pencil is substantially frusto-conical.

In order that such relations of motion between the abrading pencil and the grinding surface of the grinding wheel shall be true relations, I provide the ring arrangement for the securing end of the abrading pencil. The abrading pencil may be placed in a suitable mold 55. The abrading pencil is placed in the mold with its mesne axis coincident with the axis of the mold. The diameter of the mold may be greater than the diameter of the abrading pencil to allow for variations in the latter, the space

between the abrading pencil and the wall of the mold being provided with a filling 56, as of molders' clay. The arrangement forms an annular space 57 between the reduced end 26 of the body of the abrading pencil and the wall 58 of the mold.

A core 59, shown as a stem, is placed in the bore 30 so as to be coincident with the axis of the mold. Flowable metal is then caused to flow into the mold into said annular space to form the ring, the metal also preferably being received across the end of said reduced end of the abrading pencil to form a flange 60, whereby a cap is formed, having a central hole 61 coincident with the bore of the pencil, to form a clearance space for the bore, through which refuse due to the abrading may pass.

The flowable material employed is preferably one which is readily received in the interstices, recesses or pores in the outer periphery of the reduced end of the pencil and in the end of the latter, so as to form an intimate and non-yielding connection between said ring or cap and the body of the abrading pencil. The metal, upon cooling, shrinks about the body of the abrading pencil for more intimate connection therewith. I have found a desirable metal of this character to be lead or lead composition which 95 will readily flow into the interstices in the surface of the abrading pencil to form close and rigid union therewith. The ring preferably forms protuberances 62 in the recesses and pores. The protuberances or projections of the metal received in the interstices in the periphery of the reduced end of the abrading pencil, in the shoulder 63 at the end of the rabbet 32, and in the end of said reduced end when a cap is employed, 100 act counter to each other in rigidly fixing the ring or cap in place.

The periphery of the ring and end of the cap may, if desired, be suitably trued with suitable tools, as by turning, to bring the 110 same into trued relation with the axis of rotation of the abrading pencil.

A positioning of the rotary abrading pencil so that its axis of rotation is proximate to a line radial to the axis of rotation of the grinding wheel and at right angles to the latter axis, will result in a dressing of the grinding wheel with a finer surface, whereas, if the rotary abrading pencil is positioned with its axis of rotation describing a chord 115 to the circle of the grinding wheel or at an angle to the vertical plane in which said right angle is located, the grinding surface will be trued or dressed with a coarser surface, the degree of coarseness depending on the degree which the axis of rotation of the abrading pencil departs from a radial position. The accuracy of the truing or dressing operation is dependent on the rigidity 120 with which the abrading pencil is held in its 130

intended or true path of rotation and this latter is determined or assured by the employment of my invention.

By the employment of my invention, accuracy of the truing and dressing operation is assured, and a great saving in the durability of the grinding surface is accomplished, and effectiveness of the grinding wheel is enhanced.

Having thus fully described my invention, what I claim as new, and desire to secure by Letters Patent, is:

1. An abrading pencil having a short body of extreme hardness provided with an exposed cylindrical outer periphery and an axial bore, said cylindrical outer periphery and said bore being concentric, and a short band of softer material cast about the end of said short body and having a cylindrical outer periphery concentric with said first-named cylindrical outer periphery, said short band of softer material being of substantially less length than the length of said exposed cylindrical outer periphery, and constructed and arranged for having a chuck provided with jaws concentric about said band in axial alignment with a shaft to which said chuck is secured.

2. An abrading pencil having a body of extreme hardness provided with a cylindrical outer periphery, an axial bore and a reduced end having a reduced cylindrical outer periphery, said cylindrical outer peripheries and said bore being concentric and a band of softer material cast about said reduced cylindrical outer periphery and having a cylindrical outer periphery substantially equal

in diameter with the diameter of said first-named cylindrical outer periphery and concentric therewith.

3. An abrading pencil having a body of extreme hardness provided with a cylindrical outer periphery and an axial bore concentric with said cylindrical outer periphery, and a cup-shaped band of softer material cast about an end of said body and comprising an end flange cast upon the butt end of said body to form a cup-shaped ferrule having a cylindrical outer periphery and provided with an axial bore connecting with and in line with said first-named axial bore, and said bores in said body and said ferrule forming a passage for refuse due to the abrading.

4. In combination, an abrading pencil having a body of extreme hardness provided with a cylindrical outer periphery, an axial bore and a reduced end having an outer periphery, said first-named outer periphery and said bore being concentric, and a cup-shaped band of soft material comprising a ring portion received in the lateral space between said reduced end and the cylinder extended of said cylindrical outer periphery and an end flange cast upon the butt end of said reduced end, and provided with an axial bore connected with and in line with said first-named bore, and said cup-shaped band having a cylindrical outer periphery concentric with said first-named cylindrical outer periphery, for the purpose described.

In testimony whereof, I have hereunto signed my name.

EDWARD R. CONNERS.
